UNITED STATES PATENT OFFICE.

AUGUST SCHUMACHER, OF NEW ROCHELLE, AND HENRY DOLL, OF NEW YORK, N. Y.

SHEET-TRACKING DEVICE.

1,233,130.

Specification of Letters Patent.

Patented July 10, 1917.

Application filed July 8, 1913. Serial No. 777,926.

To all whom it may concern:

Be it known that I, AUGUST SCHUMACHER, a subject of the Emperor of Germany, residing at New Rochelle, county of Westchester, 5 State of New York, and I, HENRY DOLL, a citizen of the United States, residing at the Bronx, in the county of New York and State of New York, have invented certain new and useful Improvements in Sheet- 10 Tracking Devices, of which the following is a specification, reference being had therein to the accompanying drawing.

Our invention relates to improvements in means for guiding or tracking perforated 15 sheets over a tracking device and has particular reference to means whereby the tracker bar may be maintained perfectly stationary and whereby the tubes connected thereto and to the valve mechanism thereof 20 may be made of rigid material instead of using rubber tubing to facilitate the movement of the bar as somewhat generally employed in the tracking devices of player pianos.

25 Our invention has particular reference to and is illustrated in the accompanying drawings in its application to the automatic tracking mechanism of a player piano.

In said accompanying drawings, Figure 1 30 illustrates in front elevation with parts broken away, an application of our invention. Fig. 2 is an enlarged cross sectional detail showing certain modifications. Fig. 3 is an enlarged cross section of the valve 35 mechanism shown in plan view in Fig. 1. Fig. 4 is a plan view looking upwardly at Fig. 3, and Fig. 5 is a section on the line 5-5 of Fig. 3.

5' is the outer frame or box within which 40 the music spools 6 and 7 are suitably mounted as shown, and 8 is the perforated sheet of music wound upon the same. The spindle 9 of the upper spool 6 it will be observed is projected toward the right by the coil 45 spring 10 upon the end of the lever 11 which in turn is projected toward the left by the spring 12 held in position by the adjustable sleeve 13 mounted thereupon. 14 is a suitable bracket suitably attached to the frame 50 or box 5' and upon which is pivotally mounted the lever 15 which is also pivotally mounted as shown at the end of the bar 11 and at its opposite extremity to the connecting bar 16 which in turn is pivotally mounted to the pneumatic 17, said pneumatic being connected to the pneumatic 18 by the bar

19 as shown. 20 indicates the exhaust tube by which air is exhausted from the pneumatics, and 21-22 indicate the tubes connected to the pneumatics 17 and 18 and to the valve mechanism to be hereinafter referred to.

23 is the tracker bar which is preferably immovably secured to the frame or box 5' by any suitable means such as the screws 65 24-24', and referring to the form of valve mechanism illustrated in Figs. 2 to 5 inclusive, it will be observed that the slidable base portion 25 of the valve mechanism is provided with an engaging key 26 which is 70 slidably mounted within the V-groove 27 of the tracker 23. 28 is a suitable bracket or support for the tracker 23 within which is mounted the finger shaft 29 carrying the pinion 30. The underside of the slidable 75 base portion 25 of the valve it will be observed is cut with teeth such as 31 which are engaged by the teeth of the pinion 32 mounted upon or secured to said finger shaft 29. This finger shaft 29 being mounted 80 within the bracket 28 upon the tracker 23, when rotated will cause said sliding base member 25 of the valve to shift laterally thereby carrying everything shown in Fig. 3 with it, except the tracker bar itself, and 85 by this means it will be observed that the valve may be adjusted to or from the edge of the perforated sheet, thus accommodating different widths of paper and without moving the tracker bar itself.

90 The tubes 21-22 leading from the pneumatics 17-18 it will be observed communicate through the slidable base 25 of the valve and by the ports therein as shown to better advantage in Figs. 2 and 3. These 95 ports it will be observed are closed by the slide member 33 provided with the engaging flange 34 which normally engages the edge of the paper. The spring 35 upon the bearing 36 it will be observed normally maintains the slide 33 in the position shown in Fig. 3. However, should the edge of the sheet bear easily against the flange 34, the tube 21 is open to the atmosphere through the port 36 thereby allowing air to enter the 100 pneumatic which in turn shifts the spool 6 so that the perforations in the sheet are again brought into registration with the perforations in the tracker bar. On the other hand, should the edge of the paper 105 recede from the projection 34, the spring 35 causes the slide 33 to follow the same thus 110

exposing the tube 22 to the atmosphere through the passage 37 and thus the other pneumatic is inflated causing the spool to shift its sheet in the reverse direction, all 5 of which is well known to those skilled in the art to which the invention relates. Accordingly, by rotating the finger piece 29 the valve can be adjusted to fit the varying widths of paper and will cause the pneumatics to shift the spools and correct registration whenever the sheet shifts out of alignment due to bad tracking or uneven cutting of the sheet. The spring 38 it will be observed serves to seat the slide 33 upon 10 the adjustable base 25.

39 indicates a fixed attachment of the tracker bar which serves as a cover or protection for the ports and as a support for the spring 38 which keeps the slide 33 seated. 40 indicates a screw by which the same may be secured, and 41 another fixed portion in the form of a block which may be secured by the screw 42. 43 to 46 inclusive indicate enlarged cut-away portions between 20 the tubes 21-22 and the perforations through the slide member 25, thus allowing for a continuance of passage even though the slide member 25 is shifted with reference to the block 41, and 48 indicates the 25 end of the covering member 39 and allows for the passage of air between said end and the edge engaging flange 34.

Of course it will be understood that various modifications may be made without departing from the spirit of the invention as 30 claimed.

We claim:

1. In combination with a tracker bar having ports communicating with a pneumatic, 40 an adjustable support having ports com-

municating with said first mentioned ports, a sliding valve upon said adjustable support adapted to uncover said ports of said adjustable support, means in combination therewith for shifting a music roll, said adjustable support adapted to be mounted to slide lengthwise of the tracker bar and having an inner end adapted to pass beneath a sheet upon said tracker bar, and an edge engaging member adapted to bear against the edge of said sheet and resilient means whereby as said sheet shifts laterally said adjustable member is shifted. 45

2. In combination with a tracker bar having ports communicating with a pneumatic, 55 an adjustable support having ports communicating with said first mentioned ports, a sliding valve upon said adjustable support adapted to uncover one of said ports of said adjustable support when moved in one direction and the other of said ports of said adjustable support when moved in the opposite direction, means in combination therewith for shifting a music roll, said adjustable support adapted to be mounted to 60 slide lengthwise of the tracker bar and having an inner end adapted to pass beneath a sheet upon said tracker bar, and an edge engaging member adapted to bear against the edge of said sheet and resilient means, 70 whereby as said sheet shifts laterally said adjustable member is shifted. 65

In testimony whereof we hereunto affix our signatures in the presence of two witnesses.

AUGUST SCHUMACHER.
HENRY DOLL.
